LIQUID STORAGE TANK EQUIPMENT

Barton S. Snow, Wheaton, Ill., assignor to T. W. Snow Construction Company, Chicago, Ill., a corporation of Illinois

Application May 27, 1938, Serial No. 210,537

2 Claims. (Cl. 137—21)

My invention relates more particularly to storage tank equipment for storing liquid, such as for example water, alongside railway tracks to be supplied to receivers on the track, as for example tenders of locomotives.

As regards the matter of tenders, those of present day railway equipment present a wide range in height which has presented a serious problem in supplying liquid storage apparatus for charging liquid into the tenders.

Furthermore, the matter of accuracy in spotting the liquid inlets of receivers on the track relative to the discharge spouts of the tanks has presented objections which it is desired be avoided.

Liquid storage apparatus as hitherto provided is so constructed that the swinging spout through which the liquid is discharged extends upwardly substantially vertically when the apparatus is not in use, requiring that the operator pull the spout down a relatively great distance to position it in the filler opening of the receiver. The spout is counterweighted by a heavy counterweight requiring for the pulling down of the spout and the holding of it in discharge position, a force substantially equal to a man's weight, thus not only requiring great effort on the part of the operator but presenting danger of injury to him, particularly in winter weather. Furthermore, such apparatus is provided with a pull rope for controlling the water-discharging valve, requiring operation by the operator while holding down the spout and necessitating exertion of considerable effort in addition to the effort necessary to hold the spout down.

The water in discharging through the spout exerts an upward thrust on the spout tending to lift it and the operator and resulting in frequent accidents to the operator.

In view of these conditions and to reduce hazards it has been the practice to limit the degree of discharge-valve opening, thus throttling the flow of liquid from the tank and requiring a correspondingly greater length of time to fill the receiver, a matter which is of considerable importance particularly in the case of tenders of large locomotives, as it is desirable that the tenders be filled as quickly as possible consistent with safety.

Certain of my objects are to provide improvements in liquid storage apparatus whereby the effort required by the operator in operating the apparatus and danger of accidents will be reduced to the minimum, and the receivers may be filled more quickly and with greater safety to the operator than hitherto possible.

Another object is to provide a highly practical construction of liquid storage tank equipment by means of which receivers, such as for example tenders, having liquid inlets at widely varying elevations may be supplied with liquid.

Still another object is to avoid the necessity of accurately spotting the receivers on the tracks relative to the tanks. Other objects will be manifest from the following description.

Referring to the accompanying drawings: 10

Figure 1 is a fragmentary, partly sectional, view in elevation of water storage tank equipment embodying my invention.

Figure 2 is an enlarged fragmentary view in vertical sectional elevation of the tank and its 15 water discharging equipment of Fig. 1.

Figure 3 is a view like Fig. 2 and constituting a continuation of the water discharging equipment shown in this figure.

Figure 4 is a section taken at the line 4 on 20 Fig. 3 and viewed in the direction of the arrow.

Figure 5 is a section taken at the line 5 on Fig. 3 and viewed in the direction of the arrow.

Figure 6 is a section taken at the irregular line 6—6 on Fig. 3 and viewed in the direction of 25 the arrow.

Figure 7 is a section taken on the same line as that on which Fig. 6 is taken but viewed in the opposite direction.

Figure 8 is a view in side elevation of a carrying frame forming a part of the equipment, and by which the outer end of the discharge spout structure of the equipment, and a portion of the water outlet valve operating mechanism, are supported.

Figure 9 is a plan sectional view taken at the irregular line 9—9 on Fig. 8 and viewed in the direction of the arrow, this view illustrating the lower chord of the frame.

Figure 10 is a plan view of the upper chord 40 of the frame of Fig. 8.

Figure 11 is an enlarged sectional view of the upper end of the tank discharging pipe and the valve mechanism controlling the discharge of water from the tank.

Figure 12 is an enlarged section taken at the irregular line 12—12 on Fig. 2 and viewed in the direction of the arrows.

Figure 13 is an enlarged sectional view taken at the line 13—13 on Fig. 2 and viewed in the direction of the arrows.

Figure 14 is a plan view partly sectional and somewhat in the nature of a diagram of the apparatus shown in Fig. 1, certain parts thereof being broken away and illustrating diagram- 55.

matically the adaptability of the discharge spout of the equipment for discharging water to the water inlet of a tender in various non-spotted positions relative to the tank and also in a position 5 in which the discharge spout, together with the supporting frame and a part of the valve operating mechanism carried by the latter, may be swung into a position closely adjacent to, and substantially parallel with, the front wall of the 10 tank to avoid obstruction to the passage of rolling stock over the adjacent track; and

Figure 15, an enlarged sectional view taken at the line 15 on Fig. 14 and viewed in the direction of the arrow.

15 The particular illustrated apparatus comprises, generally stated, a tank 16 shown as supported on a framework 17 and having a valved outlet pipe 18 for the water, shown as extending upwardly into the tank through the bottom thereof and terminating at a substantially horizontal portion 19 thereof and in a depending portion 20 located adjacent the wall 21 of the tank extending along the track 100 on which the tenders to be supplied with water from the tank, travel. 20 25 The pipe 18 connects at its portion 19, by a hollow ball and socket connection 22, with a pipe 23 supported at its outer end on a supporting frame 24 pivoted to swing laterally in either direction and also serving as a support for means for operating the valve of the discharge pipe 18. Telescoped with, and slidable along, the outer end of the pipe 23 is a spout section 25 having a downturned end 26 and through which the water discharging from the tank is supplied to the 30 35 tender.

The construction and arrangement of the parts of the apparatus is such that the pipe 23, together with the spout 25 may be swung laterally in either direction and up and down at the ball and socket connection 22 and the spout 25 run in and out on the discharge pipe 23 to any position desired, to supply tenders of widely differing heights and without requiring accurate spotting of the water inlets of the tenders relative to the tank.

40 45 The discharge pipe 18 comprises a section 27 which extends upwardly into the tank as stated; an elbow section 28 connected with the lower end of the pipe section 27; a section forming the horizontal pipe portion 19 and connected with the elbow section 27; and a pipe section 29 of elbow shape connected with the pipe portion 19, with its extreme end portion 30 depending substantially vertically as shown and shaped to afford a spherical socket 31 surrounded by an annular flange 32 forming a track for the purpose hereinafter explained.

50 55 The valve controlling the flow of water from the tank 21 to the discharge pipe 18 is represented at 33, it being of common form, slideable vertically in a stationary bearing socket 34 and cooperating at its annular seat 35 with a registering annular seat 36 secured to the upper end of the pipe 18, it being understood that the valve 33 is lifted to permit of the water flow referred to. The valve 33 is connected at a stem 37 thereon with a link 38 pivotally connected with a rocker member 39 pivoted at 40 on the elbow section 28, this rocker member being pivotally connected with another link 41 which extends lengthwise in the pipe portion 19 and pivotally connects with a rocker arm 42 mounted on a square shaft 43 journaled in a tubular extension 44 on a cap plate 45 forming a part of the pipe 60 65 70 75 section 29. The ends of the shaft 43 have fixed

thereto an upwardly extending inverted yoke 46 through an opening 47 in which a pin 48 carried by a clevis 49 straddling the upper cross bar of the yoke, extends, the pin 48 being engaged by a bar 50 disposed above the pipe section 23 and pivotally connected at 51 with an arm of a bell crank lever 52 fulcrumed at 53 on the swinging supporting frame 24 and at its other end with a bar 54 carrying at its extremity a hand pull 55 positioned in reach of the operator standing on the tender to be filled, for shifting the valve in the tank to open position.

The shaft 43 is shown as provided at opposite sides of the arm 42 with pairs of spaced apart disks 56 rigidly connected with the shaft 43 and forming journaling portions at which the shaft is journalled in the tubular extension 44, packing 57 being interposed between each pair of disks 56. Nuts 58 screwed into the ends of the tubular extension 44 and having circular openings therethrough in which the shaft 43 is rotatable, hold the washers 56 in clamped relation to the packing 57.

The supporting frame 24 which comprises bars forming an upper chord 59 and bars forming a lower chord 60 secured together by vertical and horizontal cross members, is provided at the rear end of the upper chord 59 with a rearwardly extending plate 61 apertured at 62 to receive a pivoting pin 63 supported between the forked forward end 64 of a substantially horizontal flange 65 provided on the upper end of a plate 66 interposed between the pipe portion 19 and the section 29, with an opening 67 therethrough in registration with these pipe portions, the lower end of the plate 66 being rigidly secured to the framework 17 as shown generally at 66a.

The pivot 63 is disposed above and in alignment with the axial center of the ball and socket connection 22, thereby permitting the supporting frame 24 indirectly connected to the pipe 23 as hereinafter described, to be swung with this pipe laterally in either direction without binding. The lower chord member 60 is provided at its rear end with spaced apart rollers 60a which bear against the track afforded by the flange 32 and take the thrust exerted by the frame 24 tending to swing downwardly at its outer end.

The pipe 23 and spout 25 are supported from the supporting frame 24 through the medium of counterbalancing mechanism comprising a band 68 surrounding and secured to the pipe 23 and connected with the lower forked end 69 of an upwardly extending bar 70, this bar being pivotally connected at 71 with one end 72 of a bell crank lever 73 fulcrumed at 74 on the lower chord 55 of the supporting frame. The other, depending, arm 75 of the bell crank lever is connected with one end of a compression spring 76 the other end of which is shown as connected, through the medium of a turn-buckle 77, with the arm of the bell crank 52 with which the bar 50 is connected. The spring 76 serves to yieldingly hold the pipe 23, with the spout 25, in the normal raised position shown in Figs. 2 and 3 and the valve 33 in the tank, in normal closed position and serves to return these parts of the apparatus to normal position when either is actuated out of this position; a stop member 78 depending from the frame 24 and extending above the spout 35 serving to limit the upward movement of the 70 spout and the pipe 23 carrying it.

The spout 25 is of considerably larger internal cross section than the pipe 23 to fit loosely over this pipe, the opening through the spout tapering from its rear to its front end as shown to 75

adapt the spout to be tilted downwardly at its forward end progressively greater distances in the drawing of the spout forwardly along the pipe 23. To permit of relatively free sliding movement of the spout 25 on the pipe 23 the spout is provided at its rear end with rollers 79 bearing upon the top side of the pipe 23 and to prevent the withdrawing of the spout entirely from the pipe 23 chains 80 provided at opposite sides of the pipe and spout and connected at opposite ends with these parts, are provided.

When the apparatus is not in use it is desirable that the supporting frame 24 together with the parts carried thereby, including the pipe 23 and spout 25, be swung away from the track and toward the tank into substantial parallelism with the front wall 21 of the latter as illustrated by dotted lines in Fig. 14, and to secure these parts in the position referred to when swung to the position shown in this figure or in the opposite direction to extend reversely of the position therein shown, latching means are provided. The illustrated construction of latching means comprises a spring strip 81 secured to a cross member 82 of the frame 24 and carrying a depending detent 83 presenting downwardly converging cam surfaces 84 and 85 and adapted to spring into engagement with a keeper 86 provided on the supporting frame 24, one of these keepers being provided at each side of the frame. To augment the spring action of the spring plate 81 each of the latch devices has associated therewith a coil spring 87 connected with the cross member 82 and with a depending leg 88 on the detent 83. Upon swinging the frame 24 together with the parts carried thereby to a position alongside the front wall of the tank the one of the latches adjacent thereto becomes automatically engaged with the frame for releasably holding it in position.

As will be understood from the foregoing, the pipe 23 is connected with the stationary discharge pipe of the tank by a universal connection, this feature, in conjunction with the adaptability of the spout 25 for sliding movement along the pipe 23 and downward tilting movement thereon as above referred to, adapting the outlet of the spout for movement into operative position relative to the filler openings of tenders located at widely varying elevations and regardless of accurate spotting of the filler opening relative to the tank. Thus, by way of example, the piping is shown by dotted lines in its highest and lowest points for discharge into the filler openings represented at 89 and 90 of two tenders 91 and 92, respectively; and also by dotted lines in an intermediate position for discharge into the filler opening represented at 90a of a tender 92a of an intermediate height. Furthermore, by way of example I have shown, in Fig. 14, the adaptability of the apparatus for discharging water into filler openings of tenders disposed not only directly opposite the spout when the latter extends at a right angle to the front wall 21 of the tank but also when these filler openings extend to one side of this position in either direction, even a considerable distance away from this position, which avoids the necessity of accurately spotting the filler opening of the tender relative to the tank. In other words, the engineer may roughly spot the tender relative to the tank which, as will be manifest, is of considerable importance.

An important factor which must be considered in designing liquid storage tank apparatus, of the

character requiring that the operator manually depress the filling pipe, is the force produced by the large volume and velocity of the liquid in discharging from the tank when the valve is opened and which in impinging against a surface angularly disposed to the line of flow produces great reaction. By forming the pipe 18 with a substantially vertical depending outlet portion, as represented at 30, liquid is deflected downwardly and impinges against the lower portion of the pipe 23 exerting force against the latter in a direction to swing the pipe 23 downwardly, namely, in a direction to maintain the spout in the filler opening, thus relieving the operator from the necessity of holding the pipe 23 down during the filling of a tender.

As will be understood, the effort required by the operator to shift the swinging supporting pipe and spout from their position when not in use, to their position of use in a filler opening, is relatively slight, due primarily to the fact that the pipe and spout swing in a substantially horizontal plane into and out of a position in which the spout is above the receiver, requiring but little effort on the part of the operator. Furthermore, when the spout has been positioned in the filler opening and the water turned on the tendency of the force exerted by the water is to swing the supporting pipe and spout downwardly, tending to hold the spout in the filler opening and correspondingly reducing the effort required by the operator in the manipulation of the apparatus.

The need for throttling the water-discharge valve is thus eliminated; and, without increasing the size of piping hitherto used, a greatly augmented flow of liquid from the tank may be effected with safety to the operator, resulting in quicker filling of the receiver.

As will be noted, my improved apparatus presents a number of features each contributing to reducing not only the amount of effort required by the operator to actuate the apparatus and the danger of accidents to the operator, but also the time required for filling receivers which is of considerable moment particularly in connection with the filling of the tenders of large locomotives.

Also, it will be noted that the apparatus lends itself to the so counterbalancing of its movable parts that they may be quickly moved from one position to another as desired.

While I have described my invention in connection with water storage tank equipment, I do not wish to be understood as intending to limit it thereto as certain phases of my invention may be utilized in tank storage equipment for other liquids, as for example oil.

Furthermore, while I have illustrated and described a particular construction embodying my invention I do not wish to be understood as intending to limit it thereto as the same may be variously modified and altered and the invention embodied in other forms of structure without departing from the spirit of my invention. Thus, by way of example, instead of providing the spout section 25 as an element telescoping with the pipe section 23 as shown, it may be connected with the pipe section 23 by a flexible connection such as a hollow ball and socket connection as described of the connection of the pipe section 23 with the pipe 18, such modified structure presenting certain of the advantages of the construction shown and described and

constituting a practical construction for liquids such as for example either water or oil.

What I claim as new and desire to secure by Letters Patent, is:

- 5 1. Liquid storage tank equipment comprising a tank having a discharge pipe, a valve controlling flow of the liquid through said pipe, a supporting member, valve operating means on said supporting member, a pipe section communicating at its rear end with said pipe and movable up and down at its front end, and means on said member and connected with said valve operating means for counterbalancing said pipe section and yieldingly holding said valve in closed 10 position.
- 10 2. Liquid storage tank equipment comprising a tank having a discharge pipe, a pipe section in communication at its rear end with said pipe 15

and movable laterally at its front end, a rigid supporting member for the front end of said pipe section mounted for lateral swinging movement with said pipe section and held against vertical movement, and means mounted on said member and engaging said pipe section and bodily movable with said member in the swinging movements of said member for counterbalancing the front end of said pipe section, comprising a toggle comprising pivotally connected elements 10 one of which is connected with said member and the other of which engages said pipe section and a spring on said member operatively engaging the one of said elements which is connected with said member and operating to contract said 15 toggle and exert lifting force on said pipe section through said toggle.

BARTON S. SNOW.
